CLAIM

The ornamental design for a modular electrical connector crimping tool, as shown and described.

DESCRIPTION

FIG. 1 is a top, right, front perspective view of a modular electrical connector crimping tool showing my new design; FIG. 2 is a bottom, left, rear perspective view thereof; FIG. 3 is a left elevational view thereof; FIG. 4 is a right elevational view thereof; FIG. 5 is a front side elevational view thereof; FIG. 6 is a rear side elevational view thereof; FIG. 7 is a top plan view thereof; and, FIG. 8 is a bottom plan view thereof.

The broken lines in the figures form no part of the claimed design.
